UNITED STATES PATENT OFFICE.

THOMAS GILLOTT CHARLESWORTH, OF LEICESTER, ENGLAND.

APPARATUS FOR DYEING HANKS OF WOOL.

SPECIFICATION forming part of Letters Patent No. 315,910, dated April 14, 1885.

Application filed August 26, 1884. (No model.)

To all whom it may concern:

Be it known that I, THOMAS GILLOTT CHARLESWORTH, a subject of the Queen of England, residing at Leicester, England, dyer, have invented a new and useful Improved Method or Process and Apparatus for Printing or Dyeing Hanks of Wool, Cotton, and Silk, and the like, whereof the following is a specification.

10 In the accompanying drawings, Figure 1 is a general perspective view of the machine for carrying my invention into practice, the feeding-chains, &c., being removed. Fig. 2 is a front view of the machine, partly in section; 15 and Fig. 3 is a sectional side view.

A are any suitable standards or framework. B is a trough or equivalent, in which revolves the divided roll or series of rolls C, fixed upon the shaft D, driven by the pulley 20 D' or in other convenient manner. Upon the other end of shaft D is a gear-wheel, D', meshing with another wheel, E', upon shaft E, which is revolved at the same rate as D, but in the opposite direction. Gear-wheels may 25 be placed upon both ends of the shafts, if desired.

Upon shaft E is another divided roll or series of rolls, F, corresponding with that upon shaft D, and suitable mechanism—such as the screws 30 G—may be employed for the purpose of regulating the pressure upon the rolls or for lifting the upper set. The spaces H' between the rolls may be of any required breadth and depth, and where different colors are being 35 used the trough is divided into independent sections by divisions (not shown in the drawings) which pass up into the spaces H between the lower rolls, or separate troughs may be used. If only one color is being used, these 40 divisions are not required. The rolls are best covered with felt or similar soft absorbent material, and the two sets are generally in contact. The trough B contains the liquid color mixed with gum or size, &c., in the 45 usual manner to make it adhere to the material to be dyed or printed, each division of the trough having its separate color, unless one color only is being used. There may be as many rolls upon each shaft and corresponding 50 divisions in the trough as may be required, though only three are shown in the drawings.

The method of feeding the hanks to the rolls will be understood by reference to Figs. 2 and 3. The endless chains K pass over chain-pulleys L at front and back of the machine. These chains pass clear of the ends of the rolls, the line of traverse of the upper section of the chain coinciding, or nearly so, with the point of contact of the two sets of rolls, as shown. 55 These chains K carry hooks M upon the edges facing the rolls, and the hanks (which are left out of the drawings for the sake of clearness) are hooked upon them so that they are fed sidewise to the rolls. The hanks are placed 60 upon the hooks at the front of the machine and removed at the back after passing once through the rolls.

Motion is given to the chains in any suitable manner, as by the chain-wheel N, round 70 which a corresponding chain-wheel upon the back chain-wheel shaft, O, a third endless chain, passes.

For supplying the top rolls with color a supplemental rod, P, is provided, touching rolls 75 F and revolved by toothed wheel fixed on the end of shaft, and meshing with wheel on shaft E, and dipping into a color-trough, R. This roll P is divided to correspond with F, and the trough R is also divided into sections for 80 the different colors.

S is a hand-wheel connected, by a shaft with bevel-wheels, to two right and left handed screw-shafts, one in front and one on back of rollers F and C, for opening or closing the two 85 endless chains to suit any length of hanks, as they vary according to quality.

The operation is as follows: The hank of wool or other material is fed between the rolls, as above described. In passing through the 90 rolls the hank is dyed or printed, the portion between each pair of rolls C F taking the particular color contained in that portion of the trough into which that roll C dips. Thus any number of different colors equal to the number of rolls upon shaft D may be simultaneously imparted to the hank, the spaces H leaving that portion of the hank which opposes them undyed, with very pretty effect among the bright colors, the width of these being 95 regulated by the width of the spaces H. Before entering the machine the hank is first carefully combed, so as to separate each thread from its fellows and facilitate the dyeing process.

cess. The dyeing or printing is completed by once passing the hank between the rolls, and it can then be dried in the usual manner.

Having now described my invention, I 5 claim—

1. The combination, with the divided rolls F, of the supplemental divided rolls P, and the trough R, divided into sections corresponding with the rolls, substantially as described.
2. The combination, with the divided rolls F, of the supplemental divided rolls P, and a series of troughs, R, substantially as described.
3. The combination, with the divided rolls

F C and divided trough B, of the endless traveling chains K, having on their inner or opposing edges the hooks M, on which the wool is suspended and fed sidewise to the rolls, substantially as described.

In witness whereof I have hereunto set my hand in the presence of two subscribing witnesses.

THOMAS GILLOTT CHARLESWORTH.
